CLAIM

The ornamental design for a beverage cartridge holder, as shown and described.

DESCRIPTION

FIG. 1 is a top, front, right side perspective view of a beverage cartridge holder showing a first embodiment of our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a bottom, rear, right side perspective view thereof;

FIG. 9 is a top, front, right side perspective view showing a second embodiment thereof;

FIG. 10 is a front elevational view of FIG. 9;

FIG. 11 is a rear elevational view of FIG. 9;

FIG. 12 is a right side elevational view of FIG. 9;

FIG. 13 is a left side elevational view of FIG. 9;

FIG. 14 is a top plan view of FIG. 9;

FIG. 15 is a bottom plan view of FIG. 9; and,

(Continued)

FIG. 16 is a bottom, rear, right side perspective view of FIG. 9.

The broken lines illustrate portions of the beverage cartridge holder that form no part of the claimed design. The dash-dot-dot lines shown in FIGS. 1, 2 and 6 define boundaries of the claimed design and form no part of the claimed design.

1 Claim, 8 Drawing Sheets
